UNITED STATES PATENT OFFICE.

ALBERT H. HOOVER AND EDGAR M. CLARK, OF MORRIBELL, WEST VIRGINIA.

RAILWAY-RAIL AND JOINT THEREFOR.

No. 874,073.

Specification of Letters Patent.

Patented Dec. 17, 1907.

Application filed May 13, 1907. Serial No. 373,199.

To all whom it may concern:

Be it known that we, ALBERT H. HOOVER and EDGAR M. CLARK, citizens of the United States, residing at Morribell, county of Randolph, and State of West Virginia, have invented a certain new and useful Improvement in Railway-Rails and Joints Therefor, of which the following is a specification.

Our invention relates to a new and useful improvement in railway rails and joints therefor, and has for its object to provide an exceedingly simple and effective joint which will absolutely prevent the rails from getting out of line and prevent the rails from spreading, which has heretofore been the cause of a great number of accidents with great loss of life and property, while at the same time providing for the expansion and contraction of the rails.

With these ends in view, this invention consists in the details of construction and combination of elements hereinafter set forth and then specifically designated by the claims.

In order that those skilled in the art to which this invention appertains may understand how to make and use the same, we will describe its construction in detail, referring by letter to the accompanying drawing forming a part of this specification, in which—

Figure 1 is a plan view of a rail and joint made in accordance with our improvement. Fig. 2, a longitudinal section thereof showing the manner in which the ends of the rails are locked together. Fig. 3, a view similar to Fig. 2 on a smaller scale, the ends of the rails being shown separated. Fig. 4, a section at the line $x-x$ of Fig. 1.

In carrying out our invention as here embodied, A represents one end of a rail, while B represents the opposite end of another rail, or the opposite end of the same rail, it being understood that each rail has a different formation upon opposite ends.

The end A has formed therein a longitudinal groove C in which the lug D projects, while the end B has a tongue adapted to fit within the groove C, both being beveled, as clearly shown in Fig. 4, and this tongue also has a notch F adapted to engage with the lug D, and thus limiting the longitudinal movement of the rails independent of each other, but permitting sufficient movement to compensate for expansion and contraction of the

rails, as will be readily understood. The 55 end A also has formed therewith a V-shaped nose G adapted to fit within a correspondingly shaped recess H formed in the end B, thus further preventing any sidewise displacement of the ends of the rails, and at the 60 same time forming an interlocking tread so that when the wheels of a train pass over the joint the ends of the rails will be depressed in unison so as to prevent the dubbing off of 65 their edges as is usual with the ordinary form of rail, and as is well known is the point at which the greatest wear upon the rail takes place, and it often happens that the ends of the rails become so mashed and worn as to require the removal of the whole rail long before the remainder thereof is materially worn. 70

I represents our improved chair, which consists of a base plate upon which the base of the rails rest, and having formed therewith the flanges I', which overlap the edges 75 of the base of the rails, and these flanges have cut therein the slots I² and I³, in which the spikes are placed, when being driven home, and the slots I² are such as to permit 80 the heads of the spikes to be driven in contact with the base flanges of the rails, while the slots I³ are such as to cause the heads of the spikes to be driven against the upper surface of the flanges I', thus certain of the 85 spikes will clamp the chair to the tie, while certain other of the spikes will clamp the rails to the chair.

From this description it will be seen that it will be impossible for the ends of the rails of a railway track to get out of line or for the 90 rails to spread without carrying with them the chair, thus avoiding the cause for many disastrous accidents.

Having thus fully described our invention, what we claim as new and useful, is— 95

1. A rail joint consisting of the meeting ends of two rails, one of which has formed therein a groove, a lug formed in said groove, a tongue upon the end of the opposite rail adapted to fit within said groove, a 100 notch formed in said tongue adapted to engage said lug, a nose G adapted to fit in a corresponding notch formed in the opposite rail and a chair having overhanging flanges for engaging the flanges of the base of the 105 rails, as specified.

2. In combination with the meeting ends of two rails, one of which is provided with a

tongue adapted to fit in a groove formed in the opposite rail, a chair consisting of a base plate upon which the ends of the rails are seated and overhanging flanges for engaging 5 the base flanges of the rails at their point of juncture, as specified.

In testimony whereof, we have hereunto

affixed our signatures in the presence of two subscribing witnesses.

ALBERT H. HOOVER.
EDGAR M. CLARK.
